Lyman L Thomas
Design for Stoves

Des. 1061

Lyman L. Thomas, of North Dighton, Mass.

U.S. Signor &c

Dighton Furnace Co. inventors of same device.

Letters Patent No. 1061, dated Nov. 9, 1858.

The schedule referred to in these Letters Patent and making part of the same.

To all whom it may concern:

It is known that I, Lyman L. Thomas, of Dighton, in the County of Bristol and State of Massachusetts, have invented or produced a new and original design for a composition in alto-relievo, for the ornamenting of the various parts of Stoves, and I do hereby declare that the following is a full and exact description of the same, reference being had to the accompanying drawings, making a part of this Specification. The design is made up of four parts or members, as shown in the drawings at A. B. C. & D. These members consists of a combination of "wheels" connected by scroll work, and diamonds.

The wheel (a) is composed of a pointed diamond or square,

Dec 10/61

surrounded, in a circle, by a raised edge, or bead, from this circle the strokes start out at uniform intervals and terminate in the rim of the wheel, which rim is itself composed of scroll work. These wheels being placed, in a line, at the proper and desirable distance apart, are connected together, or the spaces between them filled in, with scroll work (b) composed of small beads or lines terminating in raised points or knobs. On either side of this connecting scroll work and equi-distant from the wheels, is a raised or pointed diamond. The design thus far described, inclosed between two straight beads or fillets (c.c) composes the first member and is used upon the outer edge of the "jamb" or other part of the stove, as a border. At the desired distance from the inner side of this border the raised panel commences and on its bevelled or rising sides is the second member (B), consisting of a chain or continuous line of various sized diamonds, each raised to a point in the center (f). This member continues around the four or more sides of the panel, and is also inclosed, as in the border, between two or more straight beads or fillets (g.g).

At yet another desired or proper distance, on the inside of this second member, upon the face of the panel, is the third member (C), composed also of a chain or line of pointed diamonds or squares of uniform size and distance apart, also inclosed between straight lines or fillets (k.k), the whole member being upon a base raised a little above the face of the panel, and running parallel on all sides with the second member. In the center of the panel is the fourth member (D), of the design. This member may properly be termed the center-piece. This center-piece is composed of a wheel as described in the border, encompassed with scroll work, the whole being upon a convex base, and surrounded, in a square, by a small bead or fillet (o), which is finished at the corners in scroll line and a square, with a pointed diamond in the interior of the square.

In this design, I do not claim any particular member thereof, or any separate figure of any of the members, but what I do claim as my invention or production and desire to secure by Letters Patent, is the combination and arrangement of all the various figures or members making up the whole design, as herein set forth.

witnesses.

Lent. J. Talbot.

David Williams.
